ANTENNA ROTATOR CONTROL BOX

Paul A. Dicke, New Bremen, Ohio, assignor to Crown
Controls Company, Inc., New Bremen, Ohio

Application July 14, 1954, Serial No. 31,426

Term of patent 7 years

(Cl. D26—1)

FIG. 1

FIG. 2

FIG. 3

FIG. 4

FIG. 5

Figure 1 is a front perspective view of an antenna rotator control box, showing my new design.

Figure 2 is a side elevational view thereof.

Figure 3 is a front elevational view thereof.

Figure 4 is a top elevational view thereof.

Figure 5 is a rear elevational view thereof.

I claim:

The ornamental design for an antenna rotator control box, as shown.
